METHOD OF MAKING TINSEL GARLANDS

Philip Kranz and Albert P. Schmid, Philadelphia,
Pa., assignors to Bernard Wilmsen, Philadelphia, Pa.

Application December 10, 1936, Serial No. 115,172

4 Claims. (Cl. 41—10)

Our invention relates to a new and useful tinsel garland of the type used for decorative purposes on Christmas trees and other festive occasions and displays and to a novel method and a novel machine of and for making the same, whereby a more decorative, less expensive, and more durable tinsel garland is produced than conventional tinsels known and used heretofore.

Garland tinsels of this character have heretofore been made by the feeding into a twisting machine of one or more supporting cords or other flexible elements and one or more tinsel strands or threads which are wound or braided together with the supporting cord. Tinsel thus made must, in order to present a fluffy and attractive appearance, be made of a relatively great plurality of tinsel strands, which involves expense and relatively more complicated machinery and which also, because of the character of the tinsel strands, is rather fragile due to being thin and hence does not have enough body and enough light reflecting surfaces. Furthermore, the conventional tinsel referred to has been on the market for so long that it has become common place and hence is no longer considered very attractive and decorative.

Our invention therefore contemplates the production of a tinsel which will, due to its novelty, have an attractive appearance and thus constitute a distinct addition to the decorative art, and one in which the tinsel is possessed of more body and more light reflecting area, such tinsel being at the same time produced by a less complicated machine and at greatly reduced expense.

It is a further object of our invention to produce a tinsel which can be formed from sheet tinfoil as distinguished from strands or of any sheet material such as sheet paper used for less expensive decorations.

40 In the accompanying drawings:

Fig. 1 represents a fragmentary and diagrammatic plan view of the tinsel-making machine with a portion of the tinsel or garland formed thereby.

45 Fig. 2 represents a view in elevation of the right hand side of Fig. 1.

Fig. 3 represents a view in elevation of the left hand side of Fig. 2.

50 Fig. 4 represents a fragmentary and diagrammatic view, partly in side elevation and partly in section, showing details of construction.

Fig. 5 represents a section on line 5—5 of Fig. 1.

55 Figs. 6 and 7 represent, on an enlarged scale, views showing certain details of the structure of the garland or tinsel.

Referring to the drawings in which like reference characters indicate like parts, and describing only briefly the conventional driving mechanism of the machine, I designate a pulley adapted to be driven by any belt connecting with a source of power (not shown) to turn the shaft 2 which carries the cog wheel 4 meshing with the idle cog wheel 6 on the stub shaft 8. The cog wheel 6 turns the cog wheel 10 on the shaft 12 which carries the bevel gear 14 which meshes with the bevelled gear 16 on the stub shaft 18. The stub shaft 18 carries the cog wheel 20 meshing with the cog wheel 22 into the shaft 24. The shaft 24 carries the sprocket 26 over which passes the chain 28. The chain 28 passes over the sprocket 30 on the shaft 32 which also carries the sprocket 34 over which travels the sprocket chain 36. The sprocket chain 36 travels over the sprocket wheel 38 on the shaft 40. The shaft 40 carries the eccentric 42 to raise and lower the arm 44, the lower end of which is secured at 46 to the link 47 which is provided with the adjustment slot 48. The link 47 terminates in the plate 50, which is loosely mounted on the shaft 56 and which carries the dogs 52 which engage the ratchet wheel 54, fast on the shaft 56, so that, as the arm 44 is raised by the eccentric 42, the dogs 52 turn the ratchet wheel in the direction of the arrow. The shaft 56 carries the bottom roller 58 which has at its other end the gear 60 which meshes with the gear 62 on the shaft 64 which carries the upper roller 66 to rotate the latter. 68 designates the sheet material which is fed in a step by step manner with the intermittent rotation of the ratchet wheel 54 by the eccentric arm 44, as set forth. 70 designates any conventional adjustable tensioning mechanism for adjusting the pressure on the sheet material 68 as it passes between the rollers. The shaft 40 also carries the eccentrics 74 which intermittently raise and lower the knife or cutter 76 in synchronism with the feeding of the sheet material 68 by the rollers 58 and 66. The shaft 40 also carries the pulley 78 over which travels the belt 80 which also passes over the pulley 82 on the shaft 45 84 which carries the roller 86 rotating in the direction of the arrow and assisting in the drawing or propulsion of the sheet material 68. The cutter 76 is provided with the central notch or cut-out portion 88 which serves to retain uncut 50 the corresponding portion 69 of the sheet material 68, and further to guard against cutting of the various strands used in the braiding or the winding of the finished tinsel which will next be described. 90 designates one or more rolls of the 55

sheet material 68 of any desired width and which may be paper of one or more colors on either or both faces, or which may be tinfoil or any similar material adapted for use for decorative purposes. 5 92 designates one or more rolls of any desired metallic strands, textile threads, yarns, or other applicable flexible elements or a combination thereof, which pass over one or more guides 87 and under the roller 86. 96 designates one or 10 more supplemental rolls of metallic strands, textile threads, yarns, or other flexible elements which pass over one or more guides 87 through the opening 88 to join the strands from the rollers 82 with the sheet material 68 therebetween. 15 The ends of the strands from the rolls 96 and 92 are joined and connected to the hook 100 on the spinner 102 which is rotated by the belt or other means 104 from any desired source of power (not shown). The spinner 102 is carried by a frame 106, which is actuated longitudinally of the machine, and away from the roller 86 by the conventional mechanism now used in the making of conventional tinsel, in order to draw the tinsel or garland 108 as it emerges from the 20 machine. The main frame of the machine is provided with any desired adjusting devices 110 to vary the width according to the width of the sheet material 68. If it is desired to turn the machine by hand, the usual crank 112 may be 25 provided.

The operation is as follows:

The sheet material 68, which may be tinfoil of one or more colors on either or both of its faces or which may be paper or other satisfactory decorative sheet material from one or more rolls 90, is passed between the rollers 66 and 68 through the opening 114 and under the roller 86. The binding cord 96, which may be a single strand or which, as shown, may consist of a plurality of strands of metallic, textile or a combination of both, is passed over the guides 87 through the opening 88 and under the roller 86 and sheet material 68. Similarly, the other binding cord 92, which also may be of a single strand or a plurality of strands, as stated, travels past the guides 83 and under the roller 86 to a point above or on the upper side of the sheet material 68. The ends of the cords 96 and 92 are connected to the hook 100 which is carried by the spinner 102 to twist 40 the cords 92 and 96 together to produce the braided effect illustrated. The movement of the rocker arm 44 effects a step by step or intermittent feeding to the sheet material synchronously with the actuation of the cutter 76 by the eccentric 45 74 so that, as the sheet material 68 is advanced or fed through the opening 114, the cutter 76 descends upon it and slits it transversely from the ends of the uncut portion 69 to the longitudinal edges of the sheet material, as clearly shown 50 in Fig. 7. The cords 92 and 96 are braided about the relatively solid uncut portion 69 and the twist of the cords around the portion 69 imparts a general twist or ruffling to the finished product which gives it a full fluffy appearance and renders it highly effective and light-reflecting. In 55 the conventional making of tinsel the frame 106 which carries the spinner 102 is gradually pulled away from the roller 86 to draw the finished garland and it advances through the machine, 60 the idea being that when the frame 106 has

reached the far end of the frame of the machine, the operator stops the machine, pulls the frame over towards the roller 86, severs the completed portion of garland which is then of a predetermined length, reconnects the combined cords 92 and 96 to the hook 100, and starts the machine up again to make another length of garland or tinsel. Since the frame 106 and the means by which it is actuated from the roller 86 and pulled back towards the roller 86 are well known, it is 10 deemed unnecessary to describe them in further detail.

It will thus be seen that by our novel machine and method we produce a garland or tinsel from a single sheet of material fed at the rear of the 1 machine and we thus eliminate the necessity for using prepared tinfoil strands from a plurality of spools. It will further be seen that by braiding the binding cords over the relatively large uncut portion 69 we produce a much more 2 solid and reinforced construction and one which can stand handling and is more durable than the tinsel made from tinfoil strands in the well known manner. It will be seen that by changing the position of the fastening nut 46 in the slot 21 of the link 47, the width of the strips into which the sheet material is shredded is altered accordingly.

Having thus described our invention, what we claim as new and desire to secure by Letters 30 Patent is:

1. The method of making a tinsel or garland which consists in intermittently feeding a sheet material under a cutter, shredding the longitudinal marginal portions only of said sheet material 35 whereby a central longitudinal portion thereof is left uncut, feeding binding cords above and below said sheet material, and twisting said binding cords together to confine said central uncut portion therebetween. 40

2. The method of making a tinsel or garland which consists in automatically feeding a sheet material under a cutter, shredding the longitudinal marginal portions only of said sheet material 45 whereby a central longitudinal portion thereof is left uncut, feeding binding cords above and below said sheet material, and twisting said binding cords together to confine said central uncut portion therebetween.

3. The method of making a tinsel or garland 50 which consists in feeding a sheet material to a cutter, shredding the longitudinal marginal portions only of said sheet material into strips of predetermined width, the juxtaposed ends of said strips being connected by an uncut central 55 longitudinal portion of said sheet material, and twisting a binding cord about said central uncut portion.

4. The method of making a tinsel or garland which consists in intermittently feeding multi-colored sheet material to a cutter, shredding longitudinal marginal portions only of said sheet material into strips of predetermined width, whereby the central longitudinal portion of said sheet material is left uncut, feeding binding cords 60 above and below said sheet material and twisting said binding cords together. 65
